CAR BODY BOLSTER

Otho C. Duryea, Waterbury, Conn., assignor to
 O. C. Duryea Corporation, New York, N. Y., a
 corporation of Delaware

Application July 30, 1936, Serial No. 93,435

14 Claims. (Cl. 105—228)

This invention relates to improvements in car body bolsters and it consists of the matters hereinafter described and more particularly pointed out in the appended claims.

5 The car body bolster with which the present invention is more particularly concerned, is of the kind used in the well-known Duryea type of underframe. In such underframes, there is no rigid connection between the bolster and the center sill. 10 The center sill in such underframes passes freely through openings provided therefor in the body bolster, the connection being through cushion gears arranged between the sill and bolsters. Heretofore, such bolsters were made either as an 15 integral casting or they were built up from prefabricated plates and a center brace casting riveted together. Both the cast bolster and the riveted bolster are objectionable in certain respects.

Cast bolsters of this type are heavy and the cost 20 is high. In the riveted bolster, overlapping joints are used and this necessitates care in matching up the holes in the overlapped parts and difficulties are encountered in making tight rivets. Also, inside corner seams are present in which water 25 may lodge and thus start bolster corrosion. Again, the rivet heads on the top of the bolster require routing out of the car flooring to accommodate such heads and this, of course, adds to the expense.

30 One of the objects of the present invention is to provide a body bolster of the kind adapted for use in the Duryea type underframe and which avoids the objectionable features of the cast and the riveted bolsters.

35 Another object of the invention is to provide a bolster of this kind which is simple in design, lighter in weight than the cast or riveted bolster and which at the same time shall provide ample strength and rigidity in the finished bolster.

40 Another object of the invention is to provide a built-up body bolster construction wherein the parts are so formed and so correlated that they can be secured together by butt welding, thus eliminating overlapping joints and rough edges 45 and corners.

A further object of the invention is to provide 50 a bolster of this kind having a general box-like cross section and formed with openings in the diaphragm or shear resisting walls for the passage of the center sill, the bolster being braced in the vicinity of said openings so as to resist all stresses and strains imposed thereon in use for its intended purpose.

The above mentioned objects of the invention, 55 as well as others, together with the several ad-

vantages thereof will more fully appear as I proceed with my specification.

In the drawings:

Fig. 1 is a view partly in top plan and partly in horizontal section of a car bolster embodying 5 the preferred form of the invention, the plane of the section being indicated by the line 1—1 of Fig. 2;

Fig. 2 is a view in elevation of the bolster with parts at the left hand end thereof shown as 10 broken away better to disclose the interior construction thereof;

Fig. 3 is a transverse vertical section through the bolster on an enlarged scale as taken on the 15 line 3—3 of Fig. 1;

Fig. 4 is a vertical section through the outer end of the torque arm connection of the bolster, also on an enlarged scale and as taken on the line 4—4 of Fig. 1;

Fig. 5 is a transverse vertical section through 20 an end portion of the bolster in the plane of the side bearing bracket, as indicated by the line 5—5 of Fig. 1;

Fig. 6 is a detail transverse vertical sectional 25 view through a part of the bolster in the plane of one of the sill openings, as taken on the line 6—6 of Fig. 2;

Fig. 7 is a detail horizontal sectional view 30 through a part of the bolster as taken on the line 7—7 of Fig. 2;

Fig. 8 is a perspective view of one of the 35 pressed pan-like halves of the bolster, after the associated bracing and stiffening parts have been assembled and secured in place therein;

Fig. 9 is a fragmentary perspective view of one 40 of the pan-like halves of the bolster, illustrating a modified form of structure which may be advantageously employed;

Fig. 10 is a detail vertical sectional view 45 through a part of the bolster as taken on the line 10—10 of Fig. 3;

Fig. 11 is another vertical sectional view 50 through the bolster as taken on the line 11—11 of Fig. 3 and with the center plate omitted;

Fig. 12 is a cross section through a part of the 55 bolster, illustrating one form of the box-like section that may be employed in the improved bolster;

Fig. 13 is a view similar to Fig. 12 illustrating a modified form of box-like section which may be 60 advantageously employed in the bolster and which will be more fully referred to later;

Fig. 14 is another view similar to Fig. 12 illustrating a further modified form of box-like section which also may be advantageously employed 65

in the bolster and which will also be more fully referred to later;

Fig. 15 is a view similar to Fig. 12 illustrating still a further modified form of box-like section 5 which will be more fully referred to later;

Fig. 16 is a detail sectional view showing the structure of a butt weld employed between two right angled parts embodied in the bolster, and

Fig. 17 is a detail sectional view through 10 another form of weld which is advantageously employed in the bolster and which will be more fully referred to later.

In general, the bolster embodies a pair of 15 substantially a channel-like cross section and each including a vertical diaphragm or shear resisting web, a top horizontal flange-like tension member and a bottom flange-like compression member. The mid portion of the compression member is parallel with the tension member but the ends of said compression member incline upwardly and outwardly so that the bolster tapers toward its ends. Also, the diaphragm tapers toward the ends so that each half is wider at the 20 mid portion than it is at its ends.

At the mid portion of the diaphragm of each "pan", as each bolster half will hereinafter be referred to for brevity in expression, are aligned 25 rectangular openings, spaced equidistant on each side of the transverse median line of the bolster. These openings accommodate the free passage therethrough of the center sill of the car. Due to the presence of these openings, certain stiffening 30 elements and braces are employed at said mid portions to strengthen and reinforce the pans in the vicinity of the openings so that the bolster is not weakened by the presence of said openings. Certain of the elements associated with the rear pan project outwardly beyond its diaphragm to 35 provide a connection for the springs of the gear which cushion the relative movement between bolster and sill in use. Certain of the elements associated with the front pan, also project outwardly beyond its diaphragm to provide the connection for one end of the torque arms, the other 40 end of which is adapted for connection with an end sill forming a part of the car structure.

After the stiffening and bracing elements mentioned have been secured in position in their 45 respective pans, the top and bottom flanges providing the tension and compression members respectively, as well as certain of the end wall members, are matched in edge-to-edge engagement and welded together to form the body of the 50 bolster.

Referring now in detail to that embodiment of the invention, illustrated in Figs. 1 to 8 inclusive of the accompanying drawings, the improved bolster comprises essentially, a pair of elongated 55 pans 15 and 16 respectively. The pans which are of a channel-like cross section, comprise vertically disposed webs 17 and 18 respectively, forming the shear resisting diaphragms of the bolster, horizontal top flanges 19 and 20 respectively, forming the tension member of the bolster and horizontal bottom flanges 21 and 22 respectively, forming the compression member of the bolster. At the mid portion of the pans, the shear resisting 60 diaphragms 17 and 18 are parallel. From 65 the ends of said mid portion, they taper in opposite directions toward the plane of the free edges of the associated top and bottom flanges. The flanges 19 and 20 are flat from end-to-end, but the flanges 21 and 22 taper upwardly from the 70 ends of said mid portion toward the plane of the 75

flanges 19 and 20. At the ends of the pans are formed end walls 23 and 24 respectively.

The end walls 23—24 and the ends of the members 19—20 of both pans are provided with suitable holes for the rivets by which the ends of the finished bolster body are attached to the side sills of the associated underframe. In the outer ends of the members 21—22 or both pans near said end walls, are recesses which in the finished body bolster, coact to form openings 21a' as best 10 appear at the left hand end of Figs. 1 and 2 respectively. These openings give access for spotting the before-mentioned rivets in place and permit the application of a bucker to said rivets during the upsetting thereof.

The pans which are alike and will therefore match, are made either entirely or partly as steel stampings from the same set of dies. When said pans are assembled together as will later appear, they form a hollow body having a general box-like cross section. The edges of the flanges 19—20 and 21—22 along with the edges of the end wall 23—24 may be bevelled off as best shown in Figs. 3, 5 and 6 so that when butted together, they form a welding groove for a purpose later to appear.

In the mid portion of each diaphragm and spaced equal distances upon each side of the transverse median line thereof, coincident with the center of the center sill of the car, is a pair of rectangular openings 25—26 respectively. In the finished bolster, the openings in said diaphragms align so that center sill members 27 and 28 respectively, may pass therethrough. As best shown in Fig. 2, each sill member is in the form of a channel with its web arranged vertically and 30 with its flanges facing outwardly. In the vicinity of the bolster, the edges of the flanges in each sill member have a plate 29 welded thereto to give it a hollow box-like section at this point.

The openings 25—26 are so arranged vertically 40 that the bottom edges thereof are closer to the members 21—22 than the top edges are to the members 19—20.

The sides of the openings in the rear half, or pan 15 of the bolster body, are formed by inner 45 and outer upright stiffener plates 30 and 31 respectively, the front edges of which are arranged in the plane of the edges of the associated members 19 and 21. The top edge of the inner and outer plates 30 and 31 terminate in the plane of 50 the top edges of the openings 25 and the bottom edges of said plates rest upon the member 21. The outer corner of each plate 30, at the inner end thereof, is bevelled off as at 30a in Fig. 7 for a purpose later to appear. The inner plates 30 are 55 each provided with an outer end extension 32 of a height to pass through and outwardly beyond the opening 25 for a suitable distance. These extensions are connected together by a pair of horizontal plates 33—33. Said plates, which are arranged in vertically spaced relation, about midway between the top and bottom edges of the extensions, provide the means for connecting the link of a certain associated cushioning spring gear, not shown herein, but which is conventional in the 60 Duryea underframe. The connecting plates 33 are each formed with oppositely facing bosses 34 to receive a connecting pin whereby the link before mentioned is operatively connected to the bolster.

The outer plates 31 of the pan 15 have no extension corresponding to those on the inner plates. A line of welding 35 follows the bottom edges of both plates 31 where they engage the member 21. The outer end of each plate 31 extends into the 65 diaphragm opening 25 but not through the same 70 75

so as to lap against that edge of the diaphragm defining the outer edge of the opening 25 as best appears in Fig. 17. Another line of welding 31a is then made along the edges of said plate 31 and said edge of the opening and then an inner line of welding 31b is run in along the inside corner as defined by the right angle surfaces of the said plate 31 and diaphragm 17. These two welds which best appear in Fig. 17, provide a lap weld instead of a butt weld at this point. The plates 33-33 are welded across the ends and along one side as at 36 to the extensions 32-32 and diaphragm 17.

Between the inner stiffener plates, in a plane midway between the diaphragm 17 and the plane of the edges of the members 18 and 21 is an upright, longitudinal stiffener plate or strut 37, which is welded at its bottom edge and at its ends to the member 21 and to said inner plates 30 as indicated at 38 in Fig. 7. A second upright longitudinal stiffener plate or strut 39 is welded as at 40 at its bottom and at its ends to the member 21 and to the inner margins of said inner plates 30 respectively. This plate 39 is of the same height as the plates 30-31 and 37, before mentioned, so that the top edges of all of said plates are in the same horizontal plane. The plate 39 is formed at a point between its ends with a curved portion 41. This curved portion opens into a recess 42 in the member 21 to form one-half the opening in the bolster bottom to receive the king or center pin of the truck (not shown). Said curved portion 41 extends part way up the plate 39 from its bottom edge as appears in Fig. 3. The upright stiffener plates mentioned, function as shear resisting struts as is apparent.

Engaged upon the top edges of the upright plates 30-31, 37 and 39 is a horizontal top plate 43. This top plate is welded to the top edges of said upright plates as at 44 and is also welded to the inner face of the diaphragm member 17 as at 45. Between said top plate and the tension flange 18 and arranged in the planes of the stiffener 18 and arranged in the planes of the stiffener plates 37 and 39 are other stiffener plates 46 and 47 respectively. Said plates 46-47 have downwardly facing end hooks which engage the upper end portions of the outer plates 31 but only the hooks 46a of the plate 46 appear as in Fig. 11. These plates function as shear resisting ribs or webs between said top plate 43 and the top flange or member 18 and are welded thereto and to the upright stiffener plates 31 as appears in Fig. 11 at 48. It is to be borne in mind that the plates mentioned are welded in place during their assembly within the associated pan. By means of said hooks 46a the plates 46-47 are secured not only to the member 18 and top plate 43 but also to the outer upright plates 31-31 to form a strong rigid structure above each sill opening.

A suitable distance outwardly from the outer plate 31, I provide in each pan an upright rib plate 48 which is welded as at 50 along one vertical edge and its two horizontal edges to the diaphragm 17 and to the members or flanges 19 and 21 respectively. Said rib plates are arranged substantially in or near the planes of the side bearings to form stiffening members for the side bearings of the finished bolster.

On the outer surface of the diaphragm 17 and spaced longitudinally outward from each sill opening 25 in said web are welded angle brackets 51. Upon these brackets certain supports (not shown) are engaged and upon which the flooring of the associated car body to be supported by the bolster, is secured in place. In said diaphragm

midway between the top and bottom horizontal parallel portions of the members 18 and 21 and within the planes of the brackets just above mentioned, are openings 52-53 as appears in Fig. 2. These openings are intended for use in the finished bolster for the passage of the usual train lines and brake rods (not shown) through the bolster. Each opening is defined by an inturned flange 54 which rigidifies that part of the diaphragm in which the opening is formed. 10

On the outer surface of the diaphragm near its bottom edge and arranged in the plane of the plates 48-49, are welded short channel brackets 55 and 56. Each bracket has an inclined bottom and this inclination corresponds to the inclination of the compression member 21 at this point. The purpose of these brackets is to permit the attachment of a part of the associated side bearing (not shown). 15

The sides of the openings in the front half or pan 16 of the bolster are formed by inner and outer plates 60 and 61 arranged in the vertical planes of the inner and outer plates 30 and 41 before mentioned. The inner plates 60 have inner end portions of the same height as the plates 30-32 and they are welded to the associated pan along a line 62 following about the bottom and up along the vertical edges thereof where they engage the diaphragm. The outer plates 61 are notched at the bottom as at 63 (see Fig. 6) so as to straddle that part of the diaphragm defining the bottom of the sill openings and each plate has an extension portion 64 of a height approximating the full height of the diaphragm of the pan at this point. The top and bottom ends of these extensions are bent outwardly as flanges or wings 65 and 66 by which certain torque arms of the bolster and later to be described, are attached to the bolster. These parts of said extensions above and below the sill openings are welded as at 68 to 40 the parts of the diaphragm with which they are engaged. The inner corner of each plate 61, at the inner end thereof, is bevelled off as at 61a in Fig. 7 for a purpose later to appear. 25

Between the inner stiffener plates 60-60 of the rear pan, in a plane midway between the diaphragm 18 and the plane of the edges of the flanges 20-22, is an upright stiffener plate 69. This plate is welded at its bottom and side edges to the bottom flange 22 and to the plates 60-60 respectively. The welding mentioned appears at 10 in Fig. 7.

A second upright stiffener plate 71 is welded as at 71a along its bottom and at its ends to the inner margins of the flange 22 and of the inner plates 60. This plate 71 is of the same height as the plates 60-61 and 69 before mentioned, so that the top edges of all of said plates are in the same horizontal plane. The plate 71 is formed at a point between its ends with a curved portion 72. Said curved portion opens into a recess 73 in the member 22 to form the other half of the opening in the finished bolster bottom to receive the king or center pin before mentioned, but not shown herein. This curved portion extends part 65 way up the plate from its bottom edge as appears in Figs. 3 and 8.

Engaged upon the top edges of the plates 60-69-71 and those parts of the plates 61 within the pan 16 is a horizontal top plate 74. This top plate is welded to the top edges of the upright plates as at 75 and is also welded to the inner face of the diaphragm member 18 as at 76. Between the top plate 74 and the tension flange 20 and arranged in the plane of the stiffener plates 75

- 69 and 71 are other stiffener plates 77 and 78 respectively. These plates include end hooks similar to those 46a before mentioned and which are welded to the upright plates 61—61. The plates 5 77—78 function as shear resisting ribs or webs between the top plate 74 and the flange or member 20 and are welded thereto as at 69. The hooks mentioned in connection with the plates 77—78 appear in dotted lines as at 71a in Fig. 10. It is 10 to be borne in mind that the plates mentioned are welded in place during their assembly within the pan.

As best appears in Fig. 8, the top plate 74 terminates at its ends in the plane of the outer plates 15 61—61. However, this top plate may be formed with upwardly inclined extensions 74a beyond the outer plates 61 and these extensions may be welded at their end edges to the underside of the tension flange 20 as best appears in 74b in Fig. 9. 20 When the structure shown in Fig. 9 is employed, the plates 77—78 may terminate in the plane of the plates 61—61 and thus be devoid of the hooks 71a before mentioned or should it be desired to retain said hooks, suitable openings or recesses 25 may be formed in the extensions 74a to accommodate the passage of the same therethrough.

In Figs. 1 to 8 inclusive of the drawings, the welds heretofore described are all shown as conventional right angle corner welds, wherein one 30 of the parts has a bevelled edge to form the welding groove when said edge is engaged against another part. In Fig. 16 I have shown a form of weld which may be advantageously employed to prevent blowing through of the fused welding metal in making the welds. In said figure assume that the part 60a corresponds to one of the stiffener plates 60 and the part 69a corresponds to the right angled plate 69. Under such conditions, the edge of the part 69a is bevelled as at 69b and instead of said bevelled surface terminating as a sharp edge, that side of said part opposite said surface is offset to form a thickened backing flange 69c for engagement with the face of the part 60a. When the weld 70a is made, the flange 45 69c prevents the fused welding metal from blowing through and behind the part 69a so that a smooth perfect bond results, without hairline fissures therein, where harmful cracks may start.

A suitable distance outwardly from the outer 50 plates 61, I provide in each pan 16 an upright rib plate 80 which is welded as at 81 along one vertical edge and its two horizontal edges to the diaphragm 18 and to the members 20 and 22 respectively.

55 These rib plates 80 are so disposed that when the two pans are brought together for welding as will later appear, they will line up with the plates 49 in the pan 15 and thus coat therewith in stiffening the bolster in the plane of the associated side bearings.

In Fig. 12 there is shown a conventional transverse section through a part of one form of the finished bolster. It is to be noted from said figure that the metal in both diaphragms is of the 60 same thickness as that in the members 19—21 and members 20—22 respectively. The reason therefor is that each pan is made of a gauge suitable to resist the strains and stresses the tension and compression members of the finished bolster are to bear. By reason of the 70 vertical disposition of the diaphragms, this gauge of metal is more than sufficient for said diaphragms. In order to reduce weight and cost, the same thickness of the members 19—21 and 75 20—22 may be attained with a thinner dia-

phragm as for instance as shown in Fig. 13. In that figure it is to be noted that the two pans as a whole are made of a lighter gauge metal and on the inside of the members 19a—21a and 20a—22a, strip plates 19b—21b and 20b and 22b respectively are welded.

The plates 21b—22b are welded to the members 21a—22a as at 21c—22c while the plates 19b—20b are welded to the members 19a—20a as at 19c and 20c respectively. The welds are disposed at 10 the inside corners of the respective pans and it is intended that they be of such a cross section as to extend a short distance beyond the inside curve of the associated corner. This will eliminate any hinge action at the corners between 15 the diaphragm of the pans forming the body of the bolster and the associated tension and compression members. The strips 19b—21b and 20b—22b project laterally beyond the edges of the associated members 19a—21a and 20a—22a. 20 In the welding of the two pans together to form the bolster body, the edges of the plates 19b—21b and 20b and 22b are brought into butting relation. This spaces the opposed edges of the flanges 19a—21a and 20a—22a a slight distance 25 apart to expose margins of said plates. These edges and the margins of the stiffener plates 30 contact to form a groove in which lines of welding 19d—20d may be laid to not only join the said edges together but also to join said edges to said plate margins and to join said margins together.

The plates 19b—21b and 20b—22b extend substantially the length of the bolster body. The margins thereof before mentioned, which provide the bottom of the welding grooves also serve 35 to prevent the blowing through of the fused welding metal in making the said welds 19d—20d which also extend substantially the full length of the bolster body. It is apparent that with the construction described, the required thickness of 40 stock and requisite strength may be provided in the tension and compression members, while using diaphragms which are reduced in thickness relative to that of said tension and compression members. If desired, the flanges 45 20a—22a may be formed with lines of openings to expose portions of the plates 20b—22b and then spot welds 20x and 22x (see Fig. 13) are made in said openings to further secure said members and plates together.

Instead of using the extra plates 19b—21b and 50 20b and 22b, in the forming of the pans, a slightly heavier gauge metal may be employed and the tension and the compression members may be formed by turning portions thereof back and 55 preferably upon themselves to form the double thickness tension and compression members 19e—21e and 20e—22e respectively, as shown in Fig. 14. The edges of said flanges 19e—21e and 20e—22e respectively, are welded as at 19f—21f 60 and 20f and 22f at the side corners of the pans. In making said welds, it is desired that they be of such size as to lap upon the inner flat faces of the diaphragms. In turning the metal under as a flange, this leaves the edges of each pan 65 in a rounded condition. Therefore, when said edges are in abutting relation, preparatory to the welding operation which joins them into a bolster body, the said rounded edges coat to define a good welding groove to receive the lines 70 of welding as shown in Fig. 14.

In Fig. 15 is illustrated a further modified form of structure for the box-like structure of the body of the bolster. In said figure, 19g—21g and 20g—22g indicate the tension and compres- 75

sion flanges or members respectively and 17g and 18g indicate the diaphragms of the respective pans. It is of course understood that the tension and compression members, as well as the diaphragm of each pan, are all made of the same gauge stock.

Upon the top surfaces of the compression members 20g-22g, there are welded as at 20h-22h, stiffener plates 20i-22i. These plates 10 are wider than their associated flanges 20g-22g so that when arranged with their edges in abutting relation, this spaces the edges of the flanges 20g-22g apart to form a groove in which a line of welding 20k is laid to join the associated parts 15 together as explained in connection with Fig. 13.

As to the members 19g-21g, they are a trifle wider than the members 20g-22g. Instead of using extra stiffener plates on the underside of the members 19g-21g as in Fig. 13, it is practical to make use of the bolster cover plate as the reinforcing means. In said Fig. 15, the parts 20 of the cover plates are indicated at 19l-21l respectively, and these are spaced apart at their adjacent edges to expose parts of the members 25 19g-21g and thus form a welding groove. In this groove is laid a line of welding 19m which joins said cover plate parts together and to the members 19g-21g. The cover plates are further welded to the upper corners of the respective 30 pans as at 19n-21n respectively. With such an arrangement, the bolster cover plate acts as a reinforcement for the tension member as a whole for the bolster body.

After the parts before mentioned have been 35 welded in assembled relation in their respective pans 15 and 16, said pans are brought together with the edges of the tension and the compression members of one pan abutting those of the other pan. These edges are then welded as at 40 100 and 101 respectively, and said lines of welding extend the full length of the bolster and down the ends thereof. Of course, before these welding operations are carried out, the pans are suitably positioned to assure the registration or 45 alignment of the plates 30-31 with the plates 60 and 61.

After the two pans have been welded together as before mentioned, a center sill guide bar 102 is positioned in each corner as defined by the outer 50 surfaces of the upright stiffener plates 30-30 and 60-60 and the top plates 43-43 and 74-74 of both pans and then lines of welding 103 are made to secure said bars in place. These bars are each 55 of a rectangular cross section so as to fit snugly in their respective corners and they are of such length as to have a considerable overlap with respect to the plates they engage. These bars not only act as guides for the center sill members 27-28 but they assist in connecting the pans 60 15-16 together at these points. It is pointed out that in the application and welding of said bars, this is performed through the openings 25-26 in the pan members which give complete access thereto.

65 To form a bearing for the center sill member and to brace the bottom mid portion of the bolster parts and to tie them more securely together at this point, I provide in the spaces between the inner and outer plates 30-60 and 31-61 of both 70 pans, a member 104. This member is preferably in the form of a length of channel bar. Each member is shown herein as arranged longitudinally of the bolster with its flanges 105 facing downwardly and engaged with and welded to both compression members 21-22 by lines of welding 106. These

flanges are of such height as to bring the web 107 thereof substantially flush with the bottom edges of the openings 25-26. Lines of welding 108-109 are made to secure the ends of said channels to the plates 30-60 and 31-61.

5 The upright edges of the plates 30-60 and 31-61 respectively, are brought right to the plane of the edges of the tension and the compression members respectively, of both pans so that they substantially engage.

10 With the edges of said plates arranged in engagement as described, the bevelled edges 30a and 61a define grooves in which lines of welding 30b and 61b are laid to weld said plates together at their meeting edges. The grooves 30a are accessible for welding through the sill openings in the pan 15 and the grooves 60a are accessible for welding through the sill openings in the pan 16. It is preferable that said lines of welding be made before the bars 102 and the channel mem- 15 bers 104 have been welded in position.

20 Either before or after the pans 15 and 16 have been welded together, I provide on the outer faces of the diaphragms 17 and 18, above the sill openings 25-26 on the plane of the top plates 43, 25 the solid bars 110 and 111 respectively. The bar 110 (see Fig. 10) is of a length to extend between the planes of the upright stiffener plates 31-31 and is of a greater depth at its mid portion to 30 form opposed shoulders 112 which engage the top ends of the plate extensions 32 and the center sill guide bars 102. The bar 110 is welded at its edges to the associated diaphragm 17.

35 The bar 111 is of such a length as to extend between the extensions 64 of the plates 61 and is 35 welded at its edges to the diaphragm 18. The bars 110-111 act to form the so-called "oversolid" stops against which certain stop shoulders (not shown) on the sill engage at the limit of the cushioned movement between the center sill and 40 bolster.

45 After the bolster has been thus far assembled, it is turned bottom up and a center plate 113 is arranged in position. This plate forms part of the center bearing between the car body bolster 45 and associated truck bolster (not shown). It is made as a relatively thick metal disc having a center hole 114 which lines up with the center pin opening in the bolster as provided by the parts 41-42 and 72-73 respectively. The upper 50 corner edges of the center plate are bevelled off as best appears in Fig. 3 to provide a welding groove in which annular lines of welding 115 and 116 are formed to operatively secure the plate to the bolster.

55 As before mentioned, the bolster is of the kind embodying torque resisting arms whereby the bolster is connected either to an end sill of the underframe or to a cross bearer thereof. As shown herein, the bolster is of the kind wherein 60 the torque arms are adapted for attachment to the pan 16 either before or after the two pans 15 and 16 are welded together.

65 In the present instance, said arms will be described as attached to the pan 15 after it has been welded to the pan 16 but this is not to be considered in the restrictive sense.

70 Referring now to Figs. 1 and 3, 85-85 indicate as a whole a pair of laterally spaced torque arms, 70 each of a truss formation and comprising upper and lower arm members 86 and 87 respectively. Each arm member is preferably made of angle bar. In the case of the angle bars forming the top arm members 86, the top horizontal flanges 75

face outwardly and the vertical flanges face downwardly. The arm members 86 are arranged in a horizontal plane extending at a right angle to the pan and the inner ends of the angle bars thereof, abut and are welded as at 88 to the top end edges of the plate extensions 64 and to the wings 66 thereon, before mentioned.

In the case of the angle bars forming the bottom arm members 87, the bottom horizontal flanges face outwardly and the vertical flanges face upwardly. The arm members 87 are each welded at their inner ends as at 89 to the bottom end edges of the plate extensions 64 and to the wings 67 thereon, before mentioned.

15 The arm members 87 extend upwardly and outwardly from their inner end, toward their outer end and have horizontal outer end parts meeting in abutting relation with the outer end parts of the top arm members, the vertical 10 flanges of the angle bars of both arm members being butt welded together as at 90 in Fig. 4. At the outer ends of said arms the vertical flanges of the angle bars of both arm members are ridged or corrugated as at 91 in Fig. 1. 20 Said outer ends of said arm members are connected by a transverse bracket 92. The mid portion of said bracket is disposed in the plane of the top surfaces of the horizontal flanges of the top arm members 86 and is adapted for engagement and securement to an associated end 25 sill 85a of the car structure (see Fig. 3).

30 The end portions of said bracket are bent into downwardly offset U shape yokes or hooks 93, the vertical portions of which are corrugated 35 as at 94 in Fig. 1 for engagement with the corrugations 91 before mentioned. Top and bottom lines of welding 95—96 serve to secure the bracket to the arms. The yokes or hooks mentioned receive the top flanges of the center sill 40 members 27—28 as shown in Fig. 4, and act as guides therefor in the relative movement between the center sill and bolster body.

To resist shearing strains in said arms, in their torque resisting functions, I provide between 45 the converging vertical flanges of the arm members 86—87, inner and outer web plates 96 and 97 which are butt welded along their top and bottom edges as at 98—99 to the associated edges of said vertical flanges as best appears in Fig. 3.

50 At the outer corners as formed by the junction of the inner ends of the torque arm members 86—86 with the diaphragm 18 of the pan 16, I provide gusset plates 96^b of substantially a triangular formation. These gusset plates, only 55 one of which appears in Fig. 1, have their right angled edges welded to the edges of the horizontal flange of the associated top torque arm member and to the bent over plate extension wing 66 as well as to the diaphragm 18 as indicated by the line 96a in Fig. 1. The gusset plates 96 which are disposed with their top surface below the top surface of the torque arm member 86 and member 20 of the pan 16, not only add a further bracing effect between the torque arm members 86 and pan 16 but they serve to provide a convenient portion of the bolster as a whole to which one end of associated diagonal braces (not shown) of the underframe may be attached.

60 In the flanges 21—22, just outwardly of the plates 31—61 and 49—80 respectively, as well as between the sets of plates 30—31 and 60—61 respectively are openings 117 for the drainage of water from the interior of the bolster.

75 From the construction described, it is apparent

that the bolster is a welded one and is therefore, free from rivets or bolts.

With the bolster thus made, it forms the equivalent of an integral structure much lighter in weight but stronger and less costly to produce 5 than either a cast or a riveted structure.

Furthermore, the reduced weight of the body bolster greatly aids in contributing to a reduction in the weight of the car with which it is to be used.

10 While in describing the invention, I have referred in detail to the form, arrangement and construction of the various parts thereof, as well as to the sequence and manner of the steps in installing and welding the parts in place, the 15 same is to be considered only in the illustrative sense so that I do not wish to be limited thereby except as may be specifically set forth in the appended claims.

I claim as my invention:

20 1. A body bolster of the kind described comprising a pair of substantially matched metallic pans, each including a shear resisting diaphragm, a tension member and a compression member, the edges of said members of the pan being 25 welded together, there being a pair of laterally spaced sill openings in each diaphragm, and a bracing arrangement in each pan adjacent said diaphragm openings, each arrangement comprising a plurality of transverse and longitudinal 30 plates welded to each other and to parts of the associated pans.

2. A bolster of the kind described comprising a pair of substantially matched metallic pans, each including a shear resisting diaphragm, a top tension member and a bottom compression member, the edges of said members of the pans being welded together, there being sill openings in said diaphragms, upright transversely extending stiffener plates rising from the compression member into substantially the plane of the top of said openings, and means providing a box-like section between the top ends of the stiffener plates and the tension members and portions of the diaphragm above said openings.

45 3. A bolster of the kind described comprising a pair of substantially matched metallic pans, each including a shear resisting diaphragm, a top tension member and a bottom compression member, the edges of said members of the pans being welded together, there being a pair of laterally spaced sill openings in each diaphragm, a bracing arrangement in each pan adjacent said diaphragm openings, each arrangement comprising a plurality of transverse and longitudinal 50 plates welded to each other and to parts of the associated pans, and means welded to certain of the plates of the bracing arrangement in both pans providing guides for the center sill to extend through said openings.

60 4. A bolster of the kind described comprising a pair of substantially matched metallic pans, each including a shear resisting diaphragm, a top tension member and a bottom compression member, the edges of said members of the pans being 65 welded together, there being a pair of laterally spaced sill openings in each diaphragm, with the openings in one diaphragm aligned with those in the other diaphragm, stiffening means in each pan adjacent the openings therein and including a set of upright transverse stiffener plates, a top plate thereon and a second set of longitudinal 70 stiffener plates welded to said top plate and having parts welded to certain of said transverse stiffener plates and forming a box-like structure 75

between the diaphragms above the openings therein.

5. A bolster of the kind described comprising a pair of substantially matched metallic pans, each including a shear resisting diaphragm, a top tension member and a bottom compression member, the edges of said members of the pans being welded together, there being a pair of laterally spaced sill openings in each diaphragm, with the openings in one diaphragm aligned with those in the other diaphragm, stiffening means in each pan adjacent the openings therein and including a pair of inner and outer upright transversely extending stiffening plates, a plate secured to the top edges of said stiffener plates, upright longitudinal stiffening members between and welded to said tension member and said top plate, said longitudinal stiffener members including depending hook-like end portions engaged with and welded to said outer upright stiffener plates.

6. A bolster of the kind described comprising a pair of substantially matched metallic pans, each including a shear resisting diaphragm, a tension member and a compression member, the edges of said members of the pans being welded together, there being a pair of laterally spaced sill openings in each diaphragm, with the openings in one diaphragm aligned with those in the other diaphragm, stiffening means in each pan adjacent the openings therein and including stiffening plates welded in place, means welded to the stiffener plates of both pans and to the compression members thereof respectively, and a center sill guide bar welded to certain only of the stiffener plates of both pans.

7. A bolster of the kind described comprising a pair of substantially matched metallic pans, each including a shear resisting diaphragm, a tension member and a compression member, the edges of said members of the pans being welded together, there being a pair of laterally spaced sill openings in each diaphragm, with the openings in one diaphragm aligned with those in the other diaphragm, stiffening means in each pan adjacent the openings therein and including a set of transversely extending upright stiffener plates, a top plate welded thereto and longitudinally extending stiffener ribs between the top plates and tension members and welded to the same, a sill supporting member secured to the compression members of both pans between the stiffener plates of each set thereof and welded thereto, and a sill guide bar welded to certain of the stiffener plates of both pans and to the top plates of both pans.

8. A bolster of the kind described comprising a pair of substantially matched metallic pans, each including a shear resisting diaphragm, a tension member and a compression member, the edges of said members of the pans being welded together, there being a pair of laterally spaced sill openings in each diaphragm, with the openings in one diaphragm aligned with those in the other diaphragm, stiffening means in each pan adjacent the openings therein and including a set of transversely disposed welded upright stiffener plates, a top plate welded thereto and longitudinally extending stiffener ribs between the top plates and tension members and welded to the same, and including end portions welded to certain of the upright stiffener plates.

9. In a bolster of the kind described a pair of substantially matched pans each including a diaphragm and tension and compression members, a stiffening plate welded to each of said

members at the junction of said members with said diaphragms, said stiffening plates abutting along their free edges and spacing the edges of said tension and compression members apart so as to coact in defining grooves therebetween bottomed by marginal parts of said stiffening plates, and lines of welding in said grooves connecting said tension and compression members to each other and to their respective stiffening plates which are also connected together thereby.

10. A bolster of the kind described including a body comprising a pair of substantially matched metal pans, each including a shear resisting diaphragm, a tension member and a compression member, the longitudinal edges of said members of one pan being welded to the like edges of the members of the other pan, there being a pair of laterally spaced sill openings in each diaphragm, and means secured to and providing a bracing arrangement for the central portion of the body and formed to provide passageways connecting the sill openings in both diaphragms.

11. A bolster of the kind described including a body comprising a pair of substantially matched metal pans, each including a shear resisting diaphragm, a tension member and a compression member, the longitudinal edges of said members of one pan being welded to the like edges of the members of the other pan, there being a pair of laterally spaced sill openings in each diaphragm and each opening having inner and outer upright edges and top and bottom horizontal edges, means secured in and providing a bracing arrangement for the central portion of the body and formed to provide passageways connecting said sill openings, and means welded to the outer surface of each diaphragm and partially overlapping the top end portion of both sill openings in each diaphragm.

12. A bolster of the kind described including a body comprising a pair of substantially matched metal pans, each including a shear resisting diaphragm, a tension member and a compression member, the longitudinal edges of said members of one pan being welded to the like edges of the members of the other pan, there being a pair of laterally spaced sill openings in each diaphragm and each opening having inner and outer upright edges and top and bottom horizontal edges, means secured in and providing a bracing arrangement for the central portion of the body and formed to provide passageways connecting said sill openings, means welded to the outer surface of the diaphragm of one pan and partially overlapping the top end portion of both sill openings in said diaphragm, and means arranged perpendicular and welded to said diaphragm substantially flush with the outer edges of said openings in said diaphragm and adapted for the attachment of associated torque arms thereto.

13. A bolster of the kind described including a body comprising a pair of substantially matched metal pans, each including a shear resisting diaphragm, a tension member and a compression member, the longitudinal edges of said members of one pan being welded to the like edges of the members of the other pan, there being a pair of laterally spaced sill openings in each diaphragm, means secured to and providing a bracing arrangement for the central portion of the body, said means being formed to provide passageways connecting the sill openings in both diaphragms and being further formed in its bottom to provide a king pin recess that registers with an opening formed in the abutting edges of the com-

5 pression members of both pans, and means providing a center plate secured to the bottom surface of said compression members of both pans and having an opening therein that registers with said opening in said compression members and said king pin recess.

10 14. A bolster of the kind described including a body comprising a pair of substantially matched metal pans, each including a shear resisting dia-
10 phragm, a tension member and a compression member, the longitudinal edges of said members of one pan being welded to the like edges of the members of the other pan, there being a pair of laterally spaced sill openings in each diaphragm
15 and each opening having inner and outer up-

right edges and top and bottom horizontal edges, means secured in and providing a bracing arrangement for the central portion of the body and formed to provide pasageways connecting said sill openings, means arranged perpendicular and welded to the diaphragm of one of said pans substantially flush with the outer edges of the openings therein, means providing a torque arm welded at one end to said perpendicular means and laterally spaced gusset plates welded to the 10 said torque arms, said diaphragm and said perpendicular means respectively and adapted for the attachment of diagonal braces thereto. 5

OTHO C. DURYEA. 15
